J. J. Dilley's Design, "Aulicor" for Sliding Door, Franklin Stoves,
Assigned to Meissner, Miller, Warren & Morrison, of Troy, N. Y.

Patented Nov. 4. 1856.

Des. 848

James J. Dulley, of Troy, N.Y.
Assignor to

Fuller, Warren & Morrison, of Troy, N.Y.
Letters Patent No 848 Dated Nov. 4th 1856.

The schedule referred to in these Letters Patent and making part of the same
To all whom it may concern:

Be it known that S. J. Dulley of
the City of Troy, in the County of Rensselaer, and State of New
York, have invented or produced a new and original design

called the "Rubicon" - for a sliding door, Franklin Stove, and I do hereby declare that the following is a full and exact description of the same, reference being had to the annexed perspective-drawing, making a part of this specification.

My invention relates to the ornamental design and configuration of the top plate, A, bottom plate, B, wings, C, upper band, D, lower band, E, upper doors, F, lower doors, G, and feet, H.

The particular forms or configurations of these plates or castings are shown in the drawings. - The top plate, A, is decorated by the ornaments, a, at the front side, and b, b', at the ends, of the oval urn collar, the oval moulding, c, the tablet work d, d', and the ornaments, e, at the centre and f and g, along the upper and lower sides, of the front of this plate. - The bottom plate has the open scroll work, h, between the swelling edge moulding, i, and the compound moulding, j, of the hearth, and the carved ornaments, k, between the mouldings of the supports for the wings, C. - Only one open work wing, C, is shown in the drawing, the other wing (whose extreme outline is given in dotted lines) being an exact mate to the one which is represented with all its ornamental structure completely delineated.

The upper skeleton-like band, D, is decorated with the central top ornament, l, the central bottom ornament, m, the inside scroll ornaments, n, o, 'n, o', and the side ornaments, p, p', along the lower edge. - The lower band is ornamented with the peculiarly formed wreath surrounding the central tablet, q, and the side tablets, r, r'. - The panels of the upper doors are ornamented with the peculiarly formed scroll work composition, S. - Only one upper door is shown fully, for the other one is an exact mate to the one completely drawn. - The panels of the lower doors are decorated with the central ornament t, and its surrounding scroll work composition u. -

But one of the lower doors is fully shown, for they are exact mates. - The feet are symmetrical, and each is composed of a central leaf, v, and the side vine scrolls, w, w', both of the par-

ticular form and arrangement shown in the drawing.

Having thus described my production, what I claim as new and desire to secure by Letters Patent, is the ornamental design and configuration of the plates or castings for Franklin Stoves, herein specified and represented in the annexed drawing.—

Witnesses
John Moran,
Austin F. Park.
